US00D739726S

(12) **United States Design Patent**
Lemnios et al.

(10) **Patent No.:** **US D739,726 S**
(45) **Date of Patent:** **** Sep. 29, 2015**

(54) **DOOR PACKAGE**

(71) Applicant: **LIBERTY HARDWARE MFG. CORP.**, Winston-Salem, NC (US)

(72) Inventors: **Christine Lemnios**, Greensboro, NC (US); **Yinghong Zhang**, Guangzhou (CN); **Jeanie Matherly**, Oak Ridge, NC (US); **Matthew Klein**, Apex, NC (US); **Patrick Boehnen**, Summerfield, NC (US); **Laura Hawkins**, Madison, NC (US)

(73) Assignee: **LIBERTY HARDWARE MFG. CORP.**, Winston-Salem, NC (US)

(**) Term: **14 Years**

(21) Appl. No.: **29/480,731**

(22) Filed: **Jan. 29, 2014**

(51) LOC (10) Cl. **09-03**

(52) U.S. Cl.

USPC **D9/432**

(58) **Field of Classification Search**

USPC ..... D9/414-434, 442-445, 456-457, 542, D9/563, 600, 614-624, 655, 657, 658, 661, D9/695, 697-699, 707-708, 711, D9/772-776; D7/601, 602, 538, 540, D7/550.1; D3/202, 203.5, 203.6, 205 CPC B65D 5/00; B65D 5/001; B65D 5/0015; B65D 5/0227-5/0254; B65D 5/0045; B65D 5/18; B65D 5/2033; B65D 5/38; B65D 5/40; B65D 1/22; B65D 1/225; B65D 1/24; B65D 1/34; B65D 1/38

(57) **CLAIM**

The ornamental design for door package, as shown and described.

DESCRIPTION

FIG. 1 is a perspective view of door package according to an embodiment;

FIG. 2 is a left side view of the door package of FIG. 1; FIG. 3 is a right side view of the door package of FIG. 1; FIG. 4 is a front view of the door package of FIG. 1; and, FIG. 5 is a top and a bottom view of the door package of FIG. 1.

The broken lines are for illustrative purposes only and form no part of the claimed design.

1 Claim, 3 Drawing Sheets
